UNITED STATES PATENT OFFICE.

LOUIS STEINBERGER, OF NEW YORK, N. Y.

PRONG-INSULATOR.

No. 828,820.

Specification of Letters Patent.

Patented June 19, 1906.

Application filed July 10, 1905. Serial No. 268,952.

To all whom it may concern:

Be it known that I, LOUIS STEINBERGER, a citizen of the United States, and a resident of the city of New York, borough of Brooklyn, 5 in the county of Kings and State of New York, have invented a new and Improved Prong-Insulator, of which the following is a full, clear, and exact description.

My invention relates to insulators, my 10 more particular object being to produce a type of so-called "prong-insulator" which may be used upon either the upper side or the lower side of a cross-arm, or mounted horizontally on a support and which offers certain 15 constructional and insulating advantages, as hereinafter described, and pointed out in the claims.

Reference is to be had to the accompanying drawings, forming a part of this specification, in which similar characters of reference indicate corresponding parts in all the figures.

Figure 1 is a side elevation of the insulator as applied to a cross-arm, the latter being shown in longitudinal section. Fig. 2 is a front elevation of the insulator, the cross-arm being likewise shown in section. Fig. 3 is a vertical section through the insulator and cross-arm, and Fig. 4 is a side elevation 30 showing the insulator as occupying another position and showing the cross-arm in section.

A cylindrical member 5 is provided with a frusto-conoidal portion 6 and with oppositely disposed spouts 7, so shaped as to divert the water to the right and left, according to the view shown in Fig. 2. Intermediate of these spouts are two other spouts 8, so arranged as to divert the water when the insulator is in its reversed position. An annular bead 14 is formed around the member 5 for the purpose of providing a drip-point when the insulator is mounted horizontally into a support. This bead also increases the 45 surface across which arcing tends to take place, and this increase in surface is of course independent of the position occupied by the insulator. The cylindrical portion 5 is also provided with a threaded portion 9, 50 which may be screwed into a cross-arm 10 or into any other form of support.

The spouts 7 are provided with upturned portions 7^a, which serve as guides for the water and direct the flow of the same so as, 55 to prevent undue wetting of the cross-arm 10, as will be understood from Fig. 3. A

metallic member 11 is provided with spiral prongs 12, made exactly alike, so as to engage a wire 13 in the manner indicated in Fig. 2 by pressing upon opposite sides thereof. The wire when in position has a slight kink, due to the pressure of the prongs, as will be understood from Fig. 2.

The metallic member 11 comprises a stem portion 11^a, a neck portion 11^b, and an enlarged portion or head 11^c, the latter serving to anchor it securely within the threaded portion 9.

One of the main purposes of my pronged insulator is to facilitate the protection from the weather of either a wire or a cross-arm or other support, as the case may be, according to the position in which the insulator is placed. To protect the cross-arm or support, the insulator occupies the position indicated in Fig. 2, in which event the moisture collects and flows in opposite directions from the spouts 7. The surface of the cross-arm immediately below the spouts 7 is thus maintained comparatively dry, and the danger of an arc occurring is greatly diminished. If it be desired to protect the wire, or rather the connection between the wire and the spiral prongs 12, this is accomplished by arranging the insulator as indicated in Fig. 4. When my insulator is mounted horizontally, the annular bead near the threaded portion will act as a drip-point for the moisture and will prevent the moisture coming from the outer end of the insulator from reaching the support or wall, or vice versa. It will be seen, therefore, that the insulator above described is reversible, that it may also be used horizontally, as above stated, and that it can be used without any change whatever in its construction for protecting either a support or a conductor, and that the spouts and the bead above mentioned are so located as to produce an insulator of the highest efficiency, strength, and symmetrical form.

I do not limit myself to the exact form of insulator herein shown nor to any particular materials out of which the device is made; but I prefer to make the insulating portion out of the substance known as "electrose," the metallic member being made of iron, bronze, or any other metal.

Having thus described my invention, I claim as new and desire to secure by Letters Patent—

1. An insulator, comprising a body member of insulating material having a frusto-

- 2
- conical portion provided with spouts and with sheltering portions disposed intermediate of said spouts, and a metallic member connected with said body member of insulating material and provided with prongs disposed in alinement with said sheltering portion. 5
2. An insulator, comprising a body portion of insulating material provided with spouts, said spouts being so positioned that divers of them are staggered relatively to other spouts, and also inverted relatively thereto. 10
3. An insulator, comprising a body portion of insulating material provided with spouts, and a metallic member connected with said body portion and provided with prongs disposed intermediate of said spouts. 15
4. An insulator, comprising a body portion of insulating material provided with oppositely-disposed spouts, certain of said spouts being intermediate of certain other of said spouts and inverted relatively thereto so as to render said body portion reversible, all of said spouts being provided with raised walls for directing the flow of moisture, and a metallic member connected with said body portion of insulating material. 20
5. An insulator, comprising a metallic member and a body portion of insulating material, said body portion being provided with different groups of spouts located upon opposite sides thereof, the spouts of one group being inverted relatively to the spouts of another group. 30
6. An insulator, comprising a reversible member provided with a plurality of spouts, certain of said spouts being inverted relatively to others, and means for mounting said member. 35
7. An insulator, comprising a reversible body portion of insulating material provided with spouts, one of said spouts being inverted relatively to another, and a metallic member having a shank anchored within said body portion of insulating material and provided with means for supporting a conductor. 40

In testimony whereof I have signed my name to this specification in the presence of two subscribing witnesses.

LOUIS STEINBERGER.
